UNITED STATES PATENT OFFICE

2,563,217

LIGHT BULB MOUNTING FOR SEALED
REFLECTOR UNITS

William M. Damron, Topeka, Kans.

Application March 7, 1947, Serial No. 733,103

1 Claim. (Cl. 240—41)

1

This invention relates generally to headlamps usually used on motor vehicles and the like, and more particularly to improvements in combined lens, reflector, and bulb units usable therein, the primary object of the present invention being to provide units of this character in which the bulb can be replaced without replacing the entire unit and without opening the lens and bulb and subjecting the latter to ingress of dust, air or dirt therein.

Another important object of this invention is to provide a practical and serviceable unit of the character indicated above which, besides being simple and rugged in structure and easy to install and adjust, can readily be made up of different materials in varying forms according to different manufacturing practices.

Other important objects and advantages of this invention will be apparent from the following description and accompanying drawings, wherein for purposes of illustration only, presently preferred embodiments are set forth in detail.

In the drawings:

Figure 1 is a general top plan view of one embodiment.

Figure 2 is a fragmentary longitudinal section taken on the line 2—2 of Figure 1.

Figure 3 is a fragmentary side elevation showing the bulb adapter removed from the retainer.

Figure 4 is a left hand end elevation of Figure 1.

Figure 5 is a group prospective view showing the bulb adapter, bulb and retainer separated from each other.

Figure 6 is a fragmentary side elevation, partly in vertical longitudinal section, of another embodiment of this invention.

Figure 7 is a left hand end elevation of the form of retainer including the bulb employed in the embodiment of Figure 6.

Referring in detail to the drawings, and first to Figures 1 through 5 thereof, the numeral 8 generally designates an embodiment of this invention comprising a parabolic or tear-drop type of reflector element 9 whose forward end is closed and sealed by a lens 10, and whose rear end is truncated as indicated at 11 and provided with a concentric forwardly curved inner lens 12 having a peripheral flange 13 engaging a similar flange 14 on the truncated end of the reflector and defining the opening 15 closely receiving the inner lens 12.

The replaceable bulb 16 is of the type having a mounting flange 17 formed at circumferential intervals with bayonet slots 18, the bulb being mounted on a flat disk adapter 19 having bayo-

nets or headed pins 20 on its forward side for engaging in the bayonet slots 18 in a well known manner for securely connecting the bulb 16 with its flange 17 engaging the forward side of the adapter 19, as shown in Figure 2, with the base of the bulb extending inwardly through a hole in the adapter.

The adapter 19 carrying the bulb 16 is removably mounted on the truncated rear end of the reflector 9 by means of a flat frusto-conical pan-shaped retainer 21 having angularly outset ears 22 on its peripheral flange 23 formed with holes 24 to pass screws 25 which are threadable into anchor ears 26 appropriately fastened to the outside of the reflector 9 near the rear end thereof.

The peripheral flange 23 of the retainer 21 engages the inner lens flange 13 so as to hold the same in place against the back of the reflector flange 14, thereby assembling the inner lens 12, the bulb adapter 19, and the bulb 16 in accurately axially aligned relation to each other and to the reflector 9. As indicated in Figure 2, the bulb adapter 19 seats in a conforming opening 27 formed in the center of the retainer 21, defining an annular flange 28 against the back of which the marginal portions of the adapter having bayonet slots 29 for receiving headed pins 30 on the annular flange 28 for securing the combined bulb and adapter removably in place on the retainer 21. The adapter has projecting lugs 31 facilitating turning it relative to the retainer 21.

It is obvious that in the above described embodiment the bulb 16 may be removed either by removing the retainer 21 by loosening the screws 25 and then removing the bulb adapter 19 from the retainer, and the bulb from the adapter; or more conveniently, the bulb may be removed for replacement simply by removing the adapter 19 by turning it relative to the retainer 21 in a direction to disconnect the bayonet slots and headed pins, whereby the bulb 16 can be turned relative to the adapter 19 to disconnect the bayonet slots and headed pins. Reversal of the above procedures is followed in replacing a bulb.

Referring now to Figures 6 and 7, wherein another embodiment of this invention, generally designated 8a, is shown, the overall construction is substantially the same as that of the above described embodiment, but differs therefrom in that the inner lens 12a is secured in place by cementing or otherwise securing the flange 13a permanently in place on the flange 14a, and in that the bulb adapter, as such, is eliminated, and the bulb 16a mounted directly on the retainer

21a, which itself is somewhat differently removably connected to the reflector **9a**.

In the embodiment of Figures 6 and 7, the retainer **21a** is of the same shape as the retainer **21** but the ears **22a** are pitched at the angle of the sides of the reflector **9a** and have side-opening slots **32** therein for engaging headed pins **33** on the reflector sides. In this embodiment the bottom of the retainer has only a small opening **27a** to pass the base of the bulb **16a** and the headed pins **20a** are on this bottom instead of on the adapter **19**, and in engaging these pins **20a** in the bayonet slots **18a** on the bulb flange **17a** the bulb flange engages the front side of said bottom instead of the front side of the adapter **19**. It is obvious that in this instance removal of the bulb **16a** requires removal of the retainer **21a** from the reflector, followed by removal of the bulb from the retainer **21a**, but has advantages of simplicity and small number of parts.

I claim as my invention:

A headlamp unit comprising a tapered reflector, a headlamp lens closing the forward end of said reflector, an inner lens closing the rear end of said reflector, said inner lens being forwardly curved to define a rearwardly opening bulb chamber therebehind, a removable bulb mount comprising an annular retainer positioned at the rear end of said reflector and having radial ears

5 detachably connected to points on the sides of the reflector, a light bulb having a mounting flange, and connecting means quick-detachably connecting said mounting flange to a central portion of said retainer with the bulb projecting axially into said chamber in line with the axis of the reflector, said central portion comprising a bulb adapter, and quick detachable means connecting said adapter to said retainer, said bulb being removable from the reflector through the annular retainer.

10 WILLIAM M. DAMRON.
